DESIGN FOR A COMBINED EASEL SUPPORT AND HANGER

Irving Frolick, New York, N. Y.

Application June 7, 1943, Serial No. 110,397

Term of patent 3½ years

To all whom it may concern:

Be it known that I, Irving Frolick, a citizen of the United States of America, residing in New York city, county of Bronx and State of New York, have invented a new, original, and ornamental Design for a Combined Easel Support and Hanger, of which the following is a specification, reference being had to the accompanying drawing, forming part thereof, wherein,

I claim:

The ornamental design for a combined easel support and hanger, substantially as shown.

IRVING FROLICK.
